UNITED STATES PATENT OFFICE.

HARRY F. FINNEY, OF CHICAGO, ILLINOIS, AND FRANCIS A. JACOBS, OF WARREN, OHIO, ASSIGNEES, BY MESNE ASSIGNMENTS, TO CHICAGO-CLEVELAND CAR ROOFING COMPANY, OF CHICAGO, ILLINOIS, A CORPORATION OF DELAWARE.

CAR-UNCOUPLING MECHANISM.

Application filed November 4, 1922. Serial No. 598,998.

The invention relates to a link construction for use with the uncoupling mechanism and knuckle lock of car couplings, and has for its object to provide a secure connection of this character, which permits of some relative vertical movement of the uncoupling lever, or equivalent element, and the knuckle lock towards and from each other, at the same time acting to prevent any twisting or partial rotation of the link elements on their longitudinal axes, and consequently prevent any accidental separation of the link elements from each other; the construction being such that the links may be readily assembled or disassembled by the aid of such a relative twisting or rotary movement. It is a further object to simplify the connection of the link elements with the uncoupling lever and knuckle lock so that the link elements can be readily assembled with said lever and lock, the construction at the same time being such that when so assembled the lever and lock will prevent said accidental twisting or rotating of the link elements.

With such objects in view, as well as other advantages which may be incident to the use of the improvements, the invention consists in the parts and combinations thereof hereinafter set forth and claimed, with the understanding that the several necessary elements constituting the same may be varied in proportions and arrangement without departing from the nature and scope of the invention.

In order to make the invention more clearly understood there are shown in the accompanying drawings means for carrying the same into practical effect, without limiting the improvements, in their useful applications, to the particular constructions which, for the purpose of explanation, have been made the subject of illustration.

In said drawings:

Figure 1 is an end elevation showing a portion of a railroad car and its coupling device, and an uncoupling lever construction embodying the invention.

Fig. 2 is an elevation on a larger scale showing the improved link construction, viewed in a horizontal and diagonal direction.

Fig. 3 is a similar view of the same viewed in a direction at about ninety degrees to the direction in which Fig. 2 is viewed.

Referring to the drawings 1 indicates the draw bar coupling head, 2 the knuckle lock thereon, and 3 the shaft whereby the knuckle lock is to be manipulated. This shaft extends transversely on the end of the car body 4 and is mounted in bearings 5 and 6 thereon, and is rocked as may be desired by the hand crank 7. The inner end of this shaft is provided with a crank arm 8 which is connected with the knuckle lock by a link connection A. Our invention consists in the construction of this link connection, whereby the necessary lost-motion or looseness is provided between the knuckle lock and the crank arm which operates said connection, and whereby the crank arm knuckle lock and links may be conveniently assembled, and whereby, when assembled, they cannot become accidentally disengaged. In this respect our improvement eliminates all necessity for bending or deforming the link elements, or their parts, for engagement or disengagement or security.

The link connection A comprises an upper link 9 and lower link 10, which may be interengaged with each other as shown and are provided with vertically extending slots or openings 11 whereby the knuckle lock may have vertical motion relative to said crank arm, and vice versa. The upper link is formed with a stop or head 12 which is adapted to engage one side of the crank arm and with a laterally extending element or neck 13 which extends transversely through an eye or aperture 14 of said arm. Thence the said upper link is bent downward and then upward so as to form the said slot or opening 11, and terminates in an end 15 which is transversely disposed to prevent accidental disengagement from the other link and is offset from the body of the link sufficiently to enable the upper link to be assembled with the crank arm by passing said end through the aperture 14 of the latter.

The lower link is formed with a stop or head 16 adapted to engage at one side of the eye 18 of the knuckle lock, and with a transverse element or neck 17 which is adapted to pass through and rest in the aperture of the lock, from which point the link is bent upward and is interengaged with the upper link, as shown, and thence downward so as to form the slot or opening 11, and terminates in the end 19 which is transverse-

ly disposed so as to prevent any disengagement of said upper and lower links unless one or both of them be twisted or partially rotated. This end 19 is offset from the bottom of the lower link so that said end can be passed through the eye of the knuckle lock.

The links are so shaped that they can easily interlock one with the other if either 10 link be twisted for ninety degrees or thereabouts on its longitudinal axis, but the construction is such that they cannot be separated if they are held from said twisting movement. It will be observed that the crank 15 arm holds the upper link from such movement and the knuckle lock holds the lower link from such movement, by reason of their engagement with the laterally extending elements forming the necks of said links; and 20 the crank arm can have no such twisting movement, but only a vertical movement, by reason of confinement in the bearings 5 and 6; and the knuckle lock is held from any rotation on a vertical axis by reason of its engagement in the head of the draw bar. 25 Therefore our link connection is perfectly secure after the parts have been assembled as above described.

In assembling the parts the upper link 9 30 is threaded through the eye of the lever 8 until stopped by the head 12, and the lower link 10 is threaded through the eye of the knuckle lock, until arrested by the stop or head 16, and then the links are inter-hooked 35 with each other, and finally the lever 8 is placed in proper position on the brackets 5 and 6. The parts are then ready for secure operation.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

What is claimed is—

1. A link connection for uncoupling lever constructions, for uniting the lifting mechanism with the knuckle lock, comprising upper and lower links interengaged with each other with a looseness which permits relative movement of the links both towards each other, said links being of bent rod of like size and engageable with and disengageable from each other by a twisting movement of a link, the upper and lower ends of said links respectively having laterally extending stop elements for engagement with the lifting lever and the knuckle lock, and whereby they are maintained in said engagement, and after assembly of the parts the said links being held by said laterally extending elements

from twisting movement and from disengagement from each other by the engagement therewith of the lifting lever and the knuckle lock.

2. A link connection for uncoupling lever 70 constructions, for uniting the lifting mechanism with the knuckle lock, comprising upper and lower links interengaged with each other with a looseness which permits relative movement of the links both towards each other, said links being of bent rod of like size and engageable with and disengageable from each other by a twisting movement of a link, the upper and lower ends of said links respectively having laterally extending necks 75 for engagement in the eyes of the lifting lever and of the knuckle lock, and having beyond said necks stop means for maintaining said engagement, the other ends of said links being insertable through said eyes until their necks are engaged as described, and after assembly of the parts the said links being held from twisting movement and from disengagement from each other by the engagement of the lifting lever and the knuckle 90 lock with said necks of the links.

3. A link connection for uncoupling lever 95 constructions, for uniting the lifting mechanism with the knuckle lock, comprising upper and lower links interengaged with each other with a looseness which permits relative movement of the links towards each other, said links being engageable with and disengageable from each other by a twisting movement of a link, the upper and lower 100 ends of said links respectively having laterally extending necks for engagement in the eyes of the lifting lever and of the knuckle lock, and having beyond said necks enlarged heads for maintaining said engagement, the other ends of said links being insertable through said eyes until their necks are engaged as described, and after assembly of the parts the said links being held from twisting movement and from disengagement from each other by the engagement of the lifting lever and the knuckle 110 lock with said necks of the links.

4. The combination with the knuckle lock 115 and lifting means of an uncoupling lever construction, of a link construction for uniting the lifting means with the knuckle lock, comprising upper and lower links interengaged with each other with a looseness which permits relative movement of the links towards each other, said links being engageable with and disengageable from each other by a twisting movement of a link, the upper and lower ends of said links respectively having laterally extending necks for engagement in the eyes of the lifting means and of the knuckle lock, and having beyond said necks means for maintaining said engagement, the other ends of said links being insertable through said eyes until their necks 125 130 135

are engaged as described, and after assembly of the parts the said links being held from twisting movement and from disengagement from each other by the engagement of the lifting lever and the knuckle lock with said necks of the links.

5. In an uncoupling mechanism for car couplers, the combination with a coupler lock device and means for lifting the latter, 10 of a plurality of loosely connected links forming a lost motion connection between said lock device and lifting means, the lock device and lifting means each having an eye for receiving a portion of the link adjacent thereto, the said portion of each of the links being formed as a lateral extension terminating in an enlargement, the enlargement of each of the links being disposed on opposite sides of a line connecting the lock device 20 and lifting means.

6. In an uncoupling lever construction for railway cars, the combination with the knuckle lock of a car coupler and lifting means for said lock, of a pair of telescoping 25 links loosely engaged with each other, each of said links having sidewise extensions whose ends are enlarged into knobs for loose engagement respectively with the lifting means and with the knuckle lock.

30 7. In an uncoupling mechanism for car

couplers, the combination with the coupler lock device and means for lifting the latter, 35 of a plurality of telescoping links, each of said links having an eye adapted to receive a portion of an adjacent link, said links being detachably connected to each other and to said lock device and lifting means, said links being adapted to be disengaged by a relative movement with respect to each other and each being provided with a transversely extending portion forming a stop for limiting telescoping movement of the links.

8. In an uncoupling mechanism for car couplers, the combination with a coupler lock device provided with an eye and an uncoupling lever provided with an eye, of a lost motion connection detachably connecting said lock device and uncoupling lever, said connection involving a plurality of detachable telescoping links, each of said links having 45 an extension which when in assembled position enters a corresponding one of said eyes, and the extension of each of said links being provided with an enlargement for preventing the link when in normal operative 50 position from being disassociated from the part to which it is connected.
